UNITED STATES PATENT OFFICE.

MINNIE M. CHASE, OF BUCKGROVE, IOWA.

FRUIT-BUTTER COOKER.

No. 926,240.

Specification of Letters Patent.

Patented June 29, 1909.

Application filed March 14, 1908. Serial No. 421,265.

To all whom it may concern:

Be it known that I, MINNIE M. CHASE, a citizen of the United States, residing at Buckgrove, in the county of Crawford, State of Iowa, have invented certain new and useful Improvements in Fruit-Butter Cookers; and I do hereby declare the following to be a full, clear, and exact description of the invention, such as will enable others skilled in the art to which it appertains to make and use the same.

The present invention has reference to cooking utensils and it resides primarily in the provision of an exceedingly simple, inexpensive and efficient device of that nature including a pan and a stirrer disposed within the same, the rotation of the stirrer effecting a thorough agitation of the contents of the pan during the cooking operation.

More particularly, however, the invention resides in the specific construction of the stirrer, in the particular disposition of the same with respect to the pan, and in the particular means employed for effecting the rotation of the stirrer.

This and other features which comprise the subject matter of this case will be readily understood from a consideration of the following detailed description, their preferred embodiment being illustrated in the accompanying drawings, in which corresponding parts are designated by similar reference numerals in the several views.

Of the said drawings:—Figure 1 is a vertical sectional view of the improved utensil, the section being taken longitudinally of the strap which carries the stirring mechanism. Fig. 2 is a plan view. Figs. 3 and 4 are transverse sections taken respectively on the lines 3—3 and 4—4 of Fig. 2. Fig. 5 is an enlarged detailed view of the cross arm to which the brushes are attached. Fig. 6 is a bottom plan view of the strap.

Referring more particularly to the drawings, 5 designates generally, the pan in which the butter is to be placed, and 6 the strap which is secured at opposite ends to the flanged upper edge 7 of the side wall 8 of the pan, as hereinafter described.

The pan, which is provided with a lining of enamel or porcelain has secured to its bottom a centrally-located step bearing 9, the bearing seat alining with a vertical opening 10 formed in the strap intermediate the ends thereof, said opening communicating with a circular seat 11 formed in the upper face of

the strap concentric with said opening, the diameter of said seat considerably exceeding that of the opening. This seat communicates with the inner end of a longitudinal groove 12 which is likewise formed in the upper face of the strap and opens through the adjacent end thereof.

The seat in the bearing 9 and the opening 10 in the strap are adapted to receive the opposite ends of a vertical shaft 13, the upper end of said shaft projecting a short distance into the seat 11 and carrying at such point a beveled gear 14 which meshes with a similar gear 15 secured to the inner end of a horizontal shaft 16 disposed in the groove 12, the lower portion of the last mentioned gear and the inner end of the horizontal shaft projecting into said seat. The horizontal shaft is held in place in its groove by means of a pair of bearing plates 17 whose side edges are secured to the strap, the outer end of said shaft projecting beyond the corresponding end of the strap and carrying at such point a removable collar 18. Rotation of this shaft is effected by means of a crank handle 19 fitted upon the squared reduced outer end of the shaft.

The stirring mechanism which is carried by the vertical shaft 13 comprises a horizontal cross arm 20, having a longitudinal series of openings 21 extending from end to end thereof. Through each opening is passed a wisp 22 or a plurality of wisps of corn husks, the ends of each wisp being bound together and connected with the adjacent wisps by a cord 23 which is knotted therearound. The free ends of the wisps are adapted to contact with the bottom of the pan, the ends of the wisps at one side of the vertical shaft extending in the opposite direction from those of the wisps at the other side thereof, as shown in Fig. 5. During the rotation of the vertical shaft, these wisps prevent the butter from sticking to the bottom of the pan and becoming burned. The cross arm which carries said wisps is formed on one face thereof with a vertical seat in which the shaft 13 fits, said shaft being provided with a similar seat, this construction effecting what amounts to a groove and tenon joint between said shaft and arm.

The strap 6 which supports the stirring mechanism and the horizontal drive shaft is bifurcated at one end, the bifurcation registering with a threaded opening formed through the horizontal arm of an angular

lug 24 secured to the wall 8 of the pan. Through said bifurcation and opening passes the stem of a thumb screw 25 whose head is adapted to contact with the upper face of 5 the strap. The under face of the strap is cut away at the opposite end thereof as designated by the numeral 27, to provide a space into which the upwardly bent outer end 28 of a second lug 29 extends, said bent 10 end being provided with an opening through which projects a tongue 30 secured to the under face of the strap and disposed longitudinally thereof, said tongue resting upon the flange 7 formed on the pan wall at such 15 point. By reason of this construction, it will be apparent that the strap and with it the stirring and driving mechanisms, may be readily detached from the pan when the latter is to be cleaned. The pan is further 20 provided with a pair of diametrically-opposite handles 31, which project laterally from the wall 8 thereof.

It will be apparent from the foregoing that during the operation of the device both 25 shafts are completely held against displacement; that the brushes will sweep the whole bottom of the pan and thus prevent the butter from settling and becoming burned, and that the strap with the stirring and 30 operating mechanism may be readily removed from the pan at the completion of the cooking, the lining of the pan permitting the latter to be thoroughly cleaned. In order to render the device more completely 35 sanitary, the cross arm which carries the brushes may likewise be provided with a coating of enamel or porcelain.

The entire device may obviously be manu-

factured in various sizes, the cross arm having in each instance, a length equal to the 40 diameter of the bottom of the pan.

What is claimed is:—

The combination, in a stirring implement, of a receptacle provided with a centrally-located step-bearing; a diametrically-arranged 45 strap secured at its opposite ends to the upper edge of the wall of the receptacle and having a centrally-arranged seat and a longitudinal groove formed in its upper face, the inner end of said groove communicating 50 with said seat, and an opening alining with said bearing and communicating with said seat; a vertical shaft journaled at opposite ends in said bearing and said opening and extending into said seat; a gear secured to 55 the upper end of said shaft and disposed within said seat; a cross-arm secured intermediate its ends to the lower end of said shaft, and provided with a longitudinally-arranged series of openings; a fibrous brush 60 passed through each opening and having its free ends adapted to contact with the bottom of the receptacle, the brushes at one side of said shaft extending in the opposite direction from those at the other side thereof; a 65 horizontal shaft disposed within said groove and extending at its inner end across said seat; a gear secured to said shaft and meshing with the first-mentioned gear; and means for rotating said horizontal shaft.

In testimony whereof, I affix my signature, in presence of two witnesses.

MINNIE M. CHASE.
